UNITED STATES PATENT OFFICE.

MICHAEL P. WEIMAR, OF PHILADELPHIA, PENNSYLVANIA.

BARREL-CLEANING MACHINE.

Application filed April 18, 1922. Serial No. 554,721.

To all whom it may concern:

Be it known that I, MICHAEL P. WEIMAR, a citizen of the United States, residing at Philadelphia, county of Philadelphia, State of Pennsylvania, have invented a new and useful Barrel-Cleaning Machine, of which the following is a specification.

My present invention comprehends a novel construction and arrangement of a barrel cleaning machine wherein novel means are employed for clamping the barrel in position, novel means for effecting the rotation of a barrel and novel means for adjusting the position of the support by which the barrel is carried, and locking the parts in their adjusted position.

It further comprehends a novel construction of a cleaning device which preferably comprises a chain or cable in swivelled connection with respect to a plug adapted to be substituted for the bung of the barrel, said chain or cable having connected to it a desired number of other chains or cables so that all parts of the barrel interior will be properly acted upon.

The cleansing of steel barrels which serve as containers for lubricants and sticky materials has always been a difficult proposition and my present invention is designed to overcome the difficulties which have heretofore arisen in the effectual cleaning of barrels of this character.

Other novel features of construction and advantage will hereinafter more fully appear in the detailed description and the appended claims.

For the purpose of illustrating my invention, I have shown in the accompanying drawings a typical embodiment thereof which is at present preferred by me, since this embodiment will be found in practice to give satisfactory and reliable results. It is, however, to be understood that the various instrumentalities of which my invention consists can be variously arranged and organized and that my invention is not limited to the precise arrangement and organization of these instrumentalities as herein shown and described.

Figure 1 represents an end elevation of a barrel cleaning machine, embodying my invention.

Figure 2 represents a side elevation of the means to rotate the barrel support.

Figure 3 represents in end elevation and in detached position a locking disc employed.

Figure 4 represents a section on line 4—4 of Figure 1.

Figure 5 represents, in side elevation, a portion of the barrel cleaning means.

Similar numerals of reference indicate corresponding parts.

Referring to the drawings.

1 designates the base or foundation which in practice is preferably constructed of structural metal beams secured together in any desired manner, 2 designates a standard in which is journaled the main driving shaft 3 which is provided with a tight and a loose pulley 4 and 5, respectively, in order to adapt it to receive a driving belt, (not shown). Rotatably mounted on the driving shaft 3 is a bracket 6 which is connected to the support 7 which is in the form of a skeleton framework having the end heads 8 and 9, respectively, which are spaced by means of channel irons 10 and connected together by means of a rod 11 and the nuts 12, so that a rigid construction is provided. These longitudinal channel irons 10 are connected by the cross bars 13 to which at one side is connected the bearing bracket 6 and at the opposite side a bearing bracket 14 which is rotatably mounted on a bearing 15 journaled in the standards 16 which rises from the supporting base 1.

The main driving shaft 3 is provided with a gear 17 which meshes with a gear 18 carried by a shaft 19 suitably journaled in the support 7, being journaled in the bearing 20 and the head 9.

The shaft 19 carries the gear 21 which meshes with a gear 22 journaled in the head 9 and said gear 22 meshes with a gear 23 also journaled in the head 9. The gear 23 meshes with a pinion 24 fixed to the hub of a clamping head 25 to which latter is connected a spindle 26 fixed thereto as, for example, by means of a key 27. The spindle 26 is journaled in a bushing carried by the head 9 and is maintained in position by means of a nut 28 in threaded engagement with the spindle and bearing against the washer 29 interposed between it and the head 9. A bearing washer 30 is interposed between the head 9 and the

hub of the clamping head 25. It will thus be understood that during the revolution of the driving shaft 3 the clamping head 25 for a barrel will be continuously revolved. 6 31 designates the barrel which, in the usual manner, is provided with end flanges and the clamping head 25 is provided with annular grooves 32 to receive them. In case a small barrel is employed a cap-shaped filler member 33 is used which is secured in place by means of the angle 34 and the fastening device 35. 36 designates an adjustable barrel clamping head which may have any desired number of annular grooves and 10 which is rotatably mounted at the inner end of a longitudinally adjustable spindle 37 which is keyed in a bushing 38 carried by the head 8. The spindle 37 is provided with a shoulder 38' against which the clamping head 36 abuts, and the free end of the spindle 37 terminates in a head 39 of greater diameter than the bearing portion of the spindle and a groove 40 is provided into which is received a split washer 41 which is secured 15 in position by means of fastening devices 42.

The outer portion of the spindle 37 is threaded to receive a nut provided with a hand wheel 43 above which is positioned a collar 44 having a shoulder 45 against which 20 bears a cross bar 46 the ends of which are fixed with respect to the post 47 carried by the head 8 by means of the nuts 49.

50 designates a lock nut in threaded engagement with the spindles 37 and bearing 35 against the collar 44. The bearing sleeve 15 has secured to it a worm wheel 51 which meshes with a worm 52 journalled on the standards 16 and provided with an actuating wheel 53. The bearing sleeve 15 has secured 40 to its forward end in any desired manner a disc 54 having slots 55 in its periphery into which is adapted to extend the locking end 56 of a lever 57 which is fulcrumed on the bearing bracket 14.

45 58 designates a cone-shaped plug which is threaded in order to adapt it to be substituted for the usual bung of the barrel and this plug is provided with a polygonal shaped head 59 to facilitate its assembly and disassembly with respect to the bung hole of the barrel. The plug 58 is provided with an apertured lug 60 through which passes a bolt 61 secured in position by means of a cotter-pin 62 and passing through a swivelled member 63 through which is connected a cleaning member which as illustrated is in the form of a chain 64 to which is connected throughout its length the inner ends of a desired number of side chains 65. The shaft 55 60 which carries the worm 52 may be provided with a pulley 66 so that the bearing bracket 14 and thereby the barrel support will be continuously rotated if desired, it being understood that any desired type of power can be connected to the pulley 66.

The operation of my novel barrel cleansing machine will now be readily apparent to those skilled in this art and is as follows:—

The bung of the barrel is removed and the plug 58 secured in position so that the chains 64 and 65 are within the barrel, as will be understood by reference to Figure 4, it of course being understood that prior to the placement of the plug any desired type of cleansing solution is placed in the barrel to 70 be cleaned. The barrel is then placed on the clamping head 25 and I have provided three grooves of different diameters to position the barrel although any desired number may be employed and since in the drawings I have 80 shown a smaller sized barrel, a filler member 32 is employed on which the barrel 31 rests. The hand wheel 43 is then tightened as well as the lock nut 50 so that the barrel is in clamped position in its support 7. 85

Assuming now that the driving shaft 3 is revolving, the shaft 19 will be driven, and as this shaft is intergeared with the barrel clamping head 25, the barrel will be continuously revolved within the support 7. The 90 cleaning means in the form of chains 64 and 65 are thrown during their revolution into intimate contact with the inner walls of the barrel so that it will be effectually cleaned. The support 7 may be continuously revolved 95 in which case lever 57, shown at the right hand side of 54, is thrown out of action or, in other words, disengaged from the teeth of disc 54, shown in Fig. 3. On the other hand, if it is desired to revolve the barrel at 100 intervals the hand operating mechanism, shown at the right hand side of 54, is employed. In this case lever 57 is caused to engage with the teeth of disc 54 and the hand wheel 53 actuated to rotate support 7 105 in a desired direction.

In this manner the support can be intermittently adjusted in position so that the chains will operate on all portions of the interior wall of the barrel.

110 My machine has been found in practice to give very advantageous results and to thoroughly clean metal barrels in a manner which has not heretofore been deemed possible or practical.

115 It will now be apparent that I have devised a new and useful barrel cleaning machine which embodies the features of advantage enumerated as desirable in the statement of the invention and the above description, and while I have, in the present instance, shown and described a preferred embodiment thereof which will give in practice satisfactory and reliable results, it is to be understood that this embodiment is susceptible of modification in various particulars without departing from the spirit or scope of the invention or sacrificing any of its advantages.

120 Having thus described my invention, what 125

I claim as new and desire to secure by Letters Patent, is:

1. In a barrel cleaning machine, a barrel support, means to clamp the barrel therein, 5 a plug to replace the barrel bung, a cleaning device comprising a plurality of connected chains, one of which is swivelled to said plug, means to revolve the barrel within said support, and means to rotatably adjust 10 the position of said support.

2. In a barrel cleaning machine, a base, standards thereon, a barrel support rotatably mounted on said standards, a driving shaft, a head clamping member intergeared with 15 said driving shaft, an adjustable head clamping member on said support, and means to rotatably adjust the position of said support.

3. In a barrel cleaning machine, a barrel 20 support rotatably mounted, and having spaced heads, a barrel clamping member rotatably mounted on one head, means to effect rotation of said clamping head, a spindle adjustably carried by said other head, a barrel 25 clamping member freely rotatable on said spindle, means to lock said spindle in

its adjusted position, a locking member carried by said support and a stationary locking member with which the first locking member co-operates to fix said support in 30 the position to which it has been rotatably adjusted.

4. In a barrel cleaning machine, spaced clamping heads, connections between said heads, a barrel clamping member rotatably mounted in one of said heads, means to rotate said barrel clamping member, a spindle longitudinally adjustable in the other clamping head, a barrel clamping member freely rotatable on said spindle, a 40 bar carried by and spaced from said spindle carrying head, a collar engaging said bar, an adjusting nut between said collar and said head and in threaded engagement with said spindle, a lock nut on said spindle, and means to rotatably adjust the clamping heads and thereby the barrel clamped therebetween. 45
